(57) **CLAIM**

The ornamental design for a covered wagon canopy, as
shown and described.

DESCRIPTION

FIG. 1 is a rear, right side perspective view of a covered
wagon canopy showing our new design;
FIG. 2 is a front, left side perspective view thereof;
FIG. 3 is a left side elevational view thereof;
FIG. 4 is a right side elevational view thereof;
FIG. 5 is a front elevational view thereof; and,
FIG. 6 is a rear elevational view thereof.

The broken lines shown in the drawings are for the purpose
of illustrating portions of the article and form no part of the
claimed design.
